UNITED STATES PATENT OFFICE

JOHN PURCELL, OF CHICAGO, ILLINOIS

METAL DOOR

Application filed March 24, 1930. Serial No. 438,321.

My invention relates to metal bottom doors or drop doors for railroad cars, dump trucks and the like, being particularly intended for use on gondola cars; and involves door constructions consisting of separately fabricated or cast metal frames and separate metal panels, either of sheet metal or cast steel; the panels being adapted to be removably secured to the metal frame members so as 10 to permit easy replacement when occasion requires without the necessity of a complete renewal of the entire door structure.

Another object of my invention is to provide a metal door structure which may be 15 more readily cast or fabricated than is the case with a single piece cast door which is subject to warping in the casting process; at the same time my invention obviating the necessity of carrying entire door structures 20 in stock.

The objects and advantages of my invention will be readily comprehended from the detailed description of the accompanying drawings, wherein—

25 Figure 1 is a plan view, with portions broken away, of one form of my improved door.

Figure 2 is a side elevation thereof.

Figure 3 is a detail sectional view taken 30 substantially on the line 3—3 of Figure 1 looking in the direction of the arrows.

Figure 4 is an end elevation of the door illustrated in Figure 1, as viewed from the right hand end thereof.

35 Figure 5 is a transverse sectional view taken on the offset line 5—5 of Figure 1, as viewed by the arrows.

Figure 6 is an enlarged detail sectional view taken on the line 6—6 of Figure 1, as 40 viewed by the arrows.

Figure 7 is a plan view of part of a door, with portions broken away, showing a modification.

45 Figure 8 is a detail sectional view, taken on the offset line 8—8 of Figure 7, as viewed by the arrows.

Figure 9 is a plan view of a portion of a door, parts being broken away, showing another modified form.

50 Figure 10 is a detail sectional view, taken

on the offset line 10—10 of Figure 9, as viewed by the arrows.

Figure 11 is a similar sectional view, as Figure 10, illustrating another modification.

Figure 12 is a plan view with portions 55 broken away showing a further modification.

Figure 13 is a detail sectional view taken substantially on the line 13—13 of Figure 12, as viewed by the arrows.

Figure 14 is a plan view of another modified form. 60

Figure 15 is a detail sectional view, taken substantially on the line 15—15 of Figure 14, as viewed by the arrows.

Figure 16 is a plan view of a further modification. 65

Figure 17 is a detail sectional view taken substantially on the line 17—17 of Figure 16, as viewed by the arrows.

My invention relates more particularly to 70 metal bottom doors for gondola cars which are hingedly secured at one of the ends to the car underframe, for example to the center sill of the underframe, so as to permit the doors to drop downwardly at their free ends for the purpose of dumping the material; my improved doors being especially intended for all steel cars. 75

As my invention relates to the door construction itself and not to the manner of hinging or locking the doors in place (as any of the present day methods of hinging and fastening may be employed) illustration of the doors as applied to a car is not deemed necessary. 80

In the particular exemplification of my invention, as illustrated in the first six figures of the drawings, the metal frame of the door, which is preferably of cast steel, is shown at 20. These frames are rectangular in shape and in number in keeping with the size of the car and arranged on each side of the median line of the car. The frame comprises the inner end portion 21 provided with suitable hinge-pin receiving lugs 22. 85

The outer swinging end portion 23 is provided with lugs as at 24 with which the usual fastening levers or elements engage in supporting the doors to closed position. The frame also involves the side portions 25, 25 10

which in this instance are of similar construction.

The ends and sides all comprise the vertical body portions 26, see Figure 2, provided at top with the lateral flange portions 27; while the sides 25, 25 are also shown provided with additional reenforcing ribs as at 28.

The frame is also provided with the transversely disposed intersecting portions 29 and 30 cast integral with each other and with the respective end and side portions of the frame, as shown in Figure 1, so that the upper portions occupy substantially the same horizontal plane as the end and side portions; and these intersecting portions 29 and 30, adjacent the top, are likewise provided with the laterally disposed flanges 27. The side portions 25, 25, at points intermediate of their ends, namely at points where the side portions are integral with the transverse portions 30, are slightly depressed, as shown at 31 in Figure 2, so as to expose the ends of the upper laterally extending portion or head 32 of the transverse portion 30 arranged above the laterally disposed flanged portion 27 and thus provide for the laterally opening sockets 33, more clearly shown in Figure 6, which extend longitudinally from side to side of the door frame on opposite sides of the transverse portion 30.

The door, as illustrated in Figure 1, also involves the cast steel panels 34 of length substantially equal to the length of the door frame from end to end and of any suitable width.

The door, illustrated in Figure 1, preferably involves four panels of similar construction which rest on the tops and flanges 27 of the frame and each panel, intermediate of its ends, is provided with a pair of opposingly disposed lugs 35 cast or preferably formed integral with the panels; the lugs being arranged on the lower side of the panels and at a suitable distance beneath the main portion so as to extend into the sockets 33 beneath the head portions 32 of the transverse portion 30 of the frame, see Figure 6, and thus lock or hold the panels in proper relation with the door frame and prevent movement thereof during operation of the doors. With this structure, the intermediate panels are slid into place from opposite sides of the door frame, with their lugs 35 in interengaging or sliding relation with the transversely disposed head portion 32 of the transverse frame portion 30; the intermediate panels being brought into abutting relation above the transverse frame portion 29; the outer panels 34 then being slid into place from the respective sides of the door. The outer panels are then preferably fastened in place against accidental edgewise movement by any suitable means, as for example by the use of pins 36 which pass through registering holes formed

in the outer side panels and the side portions 25 of the frame member. The pins 36 may be of a type which permit the shanks, after insertion, to be bent laterally, as shown in the drawings, to prevent their loss.

The end portions 21 and 23 of the door frame are preferably provided at their outer edges with upstanding ribs 37, which are adapted to extend substantially flush with the tops of the panels, as more clearly shown in Figure 3.

In Figures 7 and 8, I illustrate another form of my invention wherein the general frame construction is substantially identical with that previously described, involving the inner end portion 38 provided with the hinge pin receiving lugs 39 and the outer end portion 40 provided with the integral lugs 41 with which the usual fastening elements engage. In this construction, the transversely disposed portion 42 is dipped downwardly, as shown in Figure 8, so as to have the top of the other transverse portion 43 extend in a plane above the portion 42 and the top of the portion 43 is flanged laterally, as shown in Figure 8. In other words, the transverse portion 43 is substantially T-shape in cross-section. It will be also understood that the side portions of the door frame in this construction likewise dip beneath the plane of the main upper surface of the door frame in order to expose the ends of the intermediate portion of the transverse portion 43 so as to permit the door panels 44 to be slid into place from the sides of the door frame. Each of the panels employed with the structure shown in Figures 7 and 8 on its bottom face is provided with the opposingly disposed lugs 45, 45 spaced apart so as to provide a channel into which the head portion of member 43 may seat; the outer ends of the panels resting on the upper flanged surfaces 27 of the frame portions.

With this structure, like that previously described, an interlocking relation between the panels and door frame, at points intermediate of the ends of the panels, is provided; while the outer panels may be held against shifting movement by means of the pins 36 disposed through registering holes in the panels and the adjacent door frame portions.

In Figures 9 and 10 I show another modified manner of providing the interengaging relation between the panels and the door frame which consists in forming the transverse frame portion 46 with an under-cut socket 47 extending throughout its length from side to side of the door frame for the purpose of receiving the bifurcated diverging lug 48 secured to or preferably cast integral with the bottoms of the door panels 49. As shown in Figure 10, the diverging bifurcated portions of the lug 48 extend into the under-cut portion of socket 47 in the transverse portion 46 of the door frame and

thus provide an interlocking relation. The panels 49, like those previously described, are inserted from either side of the door frame by having the bifurcated diverging lugs 48 entering the end of the undercut socket 47. The door may be provided with any suitable number of panels successively slid into place, with the panels adjacent the outer sides then locked against accidental movement by the pins 36 or other suitable means.

In Figure 11, I show a sectional view of another modified method of interlocking the panels 50 with the transverse portion of the frame, namely the portion which extends from side to side.

This transverse portion 51 is substantially cylindrical to provide a substantially circular socket 52 which is open at the top in the form of a slot disposed throughout the length of the transverse door frame portion 51. Each panel 50 on its under face is provided with a spherical or rounded rib 53 which depends from the panel by means of the narrow neck portion 54. The enlarged head portion 53, as shown, is of larger diameter than the transverse dimension of the slot 55 so that an interlocking relation between the panels and the frame is provided; the panels being slid into place from either side of the frame; the panels resting on the frame portions and, like in previously described constructions, are preferably held against accidental shifting by pins 36.

In Figures 12 and 13 a still further modification is shown wherein the interengaging relation between the panels 56 and the frame is obtained at the ends of the panels. In this form, the end portions 57, 58 of the frame are provided with the overhanging or in-turned flanges 59 beneath which the ends of the panels 56 are slid; the panels being introduced edgewise from the sides of the door as in the previously described constructions; and the outer side panels may be locked in place, as by means of pins 36 which pass through registering holes in the panels and frame side portions.

Figures 14 and 15 show a further modification wherein a number of transverse portions 60, 60, extend from side to side and unite at intermediate points with the longitudinally extending portion 61.

The transverse portions 60 are each formed with a substantially T-shaped head 62, preferably integral with the upper faces of the portions 60 and therefore disposed above the plane of the main body of the portions 60, as more clearly shown in Figure 15.

The end portions of the frame are also provided with overhanging flanges or lips 63. The panels 64 are inserted into place from either side of the door frame, with the longitudinal edges of the panels 64 sliding beneath the overhanging flange 63 at either end

of the door and beneath one side of the head of the T-shaped rib 62; while the intermediate panel is slid endwise beneath the overhanging portions of the T-shaped heads 62. The ends of the panels may be locked in place by means of the pins 36 inserted through registering holes in the panels and the side portions of the door frame.

In Figures 16 and 17, I show a door construction employing corrugated panels 65. In this construction the frame side portions 66, 66 are each provided with an overhanging flange 67; while the longitudinal portion 68, which extends from end to end of the frame, is provided with a T-shaped rib 69 extending throughout the length of the portion 68. The panels 65 are inserted endwise into place from the ends of the door; the corrugations being made lengthwise of the panels so as not to interfere with the free dumping of the material. The panels 65 at the ends are shown held in place by means of the pins 36.

The various panels employed in the constructions shown in Figures 1, 7, 9 and 11 are preferably cast steel; while the panels of the constructions shown in Figures 12, 14 and 16 may be either sheet or cast steel plates; but all constructions consist of separate frame members and panel members, with the panel members arranged in interengaging or interlocking relation with the frame members, permitting, however, the ready renewal of either element of a door to be made without necessity for renewal of the entire door, thus enabling repairs to be more easily made, while at the same time obviating the necessity of carrying entire doors in stock as has heretofore been the case.

I have shown various forms of my invention which I believe to be the simplest embodiments thereof and have described the same in terms employed merely as terms of description and not as terms of limitation, as structural modifications are possible and may be made without, however, departing from the spirit of my invention.

What I claim is:

1. Metal doors of the character described comprising frame members describing the general contour of the doors; and separate panel members adapted to rest on the frame members; the frame members and the panel members being provided with interengaging portions whereby the panel members are endwisely slid into place; and means whereby the panel members are locked in position.

2. Metal doors of the character described comprising frame members and separate panel members; the frame members having longitudinally extending open-ended grooves adapted to receive portions of the panels; the panels being insertable into place from the ends of said grooves.

3. Metal doors of the character described comprising integral metallic frame members,

and separate metallic panel members; the frame members and the panel members having integral portions disposed toward opposite ends of the doors and adapted to provide interengaging relation when the panel members are slid edgewise along the upper surface of the frame members.

4. Metal doors of the character described comprising metallic skeleton frame members and metallic panel members; the frame members being provided with portions adapted to receive correlated protruding portions on the panel members, said frame member portions at opposite ends being formed to permit the panel member to be edgewise slid into holding engagement therewith from opposite ends of the frame members.

5. Metallic doors of the character described comprising metallic skeleton frame members and metallic panel members; the frame members at intermediate portions and extending from side to side and the panel members throughout their widths being provided with matching surfaces adapted to be moved edgewise into interlocking engagement whereby the panel members are held in place.

6. Metallic doors of the character described comprising metallic frame members provided with transversely disposed intermediate portions, said portions being provided with grooves extending lengthwise of the portions and open at the ends thereof; and panel members provided with portions insertible edgewise into said grooves whereby interlocking relation between the frame members and the panel members is provided.

7. Metal doors of the character described comprising skeleton frame members, the transverse intermediate portions being provided with longitudinal grooves open at the ends of said transverse portions; and metallic panels provided on their lower faces with protruding depending portions insertible at the ends of said grooves as the panels are slid flush with the upper face of the frame members whereby interlocking relation between the frame members and the panel members is provided.

JOHN PURCELL.
